UNITED STATES PATENT OFFICE.

ALBERT JACKSON THOMAS, OF CLINTON, INDIANA.

REVERSIBLE DOOR LATCH AND LOCK.

Application filed May 21, 1924. Serial No. 714,777.

This invention relates to the type of appliance that is commonly known as a mortise-lock or bolt, the invention having reference more particularly to a combined latch and lock for doors that is adapted to be quickly and inexpensively applied.

An object of the invention is to provide a door latch and lock that may be compactly constructed of simple and inexpensive parts and of such form as to be adapted to be applied in a hole bored in a door and obviate the cost commonly entailed in the making of chisled mortises required for rectangular lock cases.

Another object is to provide a reversible door latch and lock that shall be adapted to be applied for use in a simple manner without requiring expert workmanship and extremely accurate fitting of various parts together, and which shall have strong yet inexpensive parts essential to lock structure.

A further object is to provide a reversible door latch and lock which may be constructed of simple parts adapted to be produced with small cost for machine work or fine finishing operations, and which shall be strong, durable and economical in use.

With the above-mentioned and other objects in view, the invention consists in a novel apparatus for latching and locking doors provided with a cylindrical casing adapted to be applied reversibly as may be required on different doors; and the invention consists also further in the parts and combinations and arrangements of parts as hereinafter particularly described and further defined in the appended claims.

Referring to the drawings, Figure 1 is a fragmentary elevation of a door and its casing having the invention applied thereto; Fig. 2 is a fragmentary elevation of the door frame showing the front of the keeper plate thereon; Fig. 3 is a fragmentary elevation showing the edge of the door and the invention applied thereto; Fig. 4 is a perspective view of a lock key on an enlarged scale, suitable for operating the improved door lock; Fig. 5 is a horizontal longitudinal section of the latch and lock mechanism on an enlarged scale, centrally of the lock case; Fig. 6 is an end view of an improved latch bolt retractor and controller yoke; Fig. 7 is a vertical central sectional view of the latch and lock mechanism; Fig. 8 is a transverse fragmentary section approximately on the line VIII—VIII in Fig. 7 on a relatively

smaller scale; Fig. 9 is a perspective view of the principal parts of the latch and lock mechanism assembled separately from the casing thereof; and Fig. 10 is a fragmentary side view of the lock case.

Similar reference characters in the different figures of the drawings indicate corresponding elements or features of construction herein referred to in detail.

In the drawings the numeral 1 indicates a door frame which may be variously constructed, and 2 indicates a door which may be variously constructed as desired and arranged to be latched and locked to the frame. 65 An improved keeper is provided which comprises a plate 3 adapted to be secured to the door frame and having a projecting striker plate 4 on one edge thereof, the middle portion of the plate 3 having a rectangular 70 aperture 5 therein to receive a latch bolt, the plate having also recesses 6 and 6' extending from the upper and lower portions respectively of the aperture to receive the two bars of an improved lock bolt. 75

The latch and lock mechanism has a tubular or hollow cylindrical case 7 which is of suitable diameter so as to be inserted in a bore made by a standard wood boring bit, one end of the case having an end plate 8 80 fixed thereto to be seated on the edge of the door, the plate having a rectangular aperture 9 and recesses 10 and 10' extending from the upper and lower portions respectively of the aperture, similarly to that in 85 the keeper, in which to guide the latch bolt and the lock bolt. The opposite end of the case 7 has a closure which preferably is a screw plug 11 removably secured therein. 90 One side of the case has a key-hole 12 and 95 the opposite side has a key-hole 12' therein, the key-holes being arranged equal distances from the end plate 8, and each one preferably is circular. At a suitable distance from the plug 11 the case 7 has also two 100 guide holes 13 and 13' in opposite portions of the casing wall to receive a latch-operating spindle. The plate 8 is secured to the door preferably by means of screws 14.

A novel hollow cylindrical or tubular lock 105 bolt body 15 is provided which is of suitable diameter to freely slide within the lock case 7, and it has two oppositely arranged lock bars 16 and 17 fixed on the forward portion thereof that are guided in the recesses 10 and 10' respectively. The body 15 has a tension spring 18 suitably connected thereto and 110

normally pressing against the wall of the case 7 to hold the body in place except when forcibly moved by a key, the spring being arranged in a suitable recess 19. The opposite side portions of the wall of the body 15 have longitudinal slots 20 and 20' therein, one edge of the wall having rack bar teeth 21 thereon projecting towards the wall edge 22 on the opposite side of the slot, the 10 edge 22 constituting a guide for a cylindrical key 23 that is fluted or shaped as a pinion to engage the teeth 21, the key being adapted to fit closely in the key-hole 12 and being provided with an operating shank or 15 handle 24, whereby to move the lock bolt longitudinally in the lock case.

A novel latch bolt is provided which comprises a bolt head 25 that is movably guided in the aperture 9 and has a beveled outer 20 end 26, the upper and lower portions of the head that are usually horizontal having longitudinal grooves 27 and 28 respectively to receive portions of the lock bars 16 and 17, the grooves being opposite to the recesses 25 6 and 6'. The lock bolt includes also a shank 29 fixed to the back of the bolt head and extending partially through the body part 15, the shank having a cross-bar to constitute a T-head 30 on its inner end. Preferably the inner side of the body part 15 has longitudinal grooves 31 at opposite sides of the lock bars to receive the corner portions of the latch bar head, to guide the head through the body 15 when assembling 35 the parts. A novel operating and controlling frame or yoke 32 is provided which is movably guided in the casing 7 rearward of the tubular body 15, the forward portion of the frame being sufficiently narrow to enter 40 the tubular body, the frame having shoulders 33 and 33' to engage the inner end of the body. A disk plate 34 is fixed on the forward end of the frame and it has a slot 35 extending from the edge thereof to removably receive the neck of the T-head 30, whereby the shank 29 is connected to the frame to permit the latch bolt to be retracted 45 partially into an opening 36 provided in the frame 32. A coil spring 37 is arranged on the shank 29 and seated against the head 25 and the disk plate 35 for yieldingly holding the latch bolt in projected position. The rear end of the frame 32 has a circular guide plate 38 fixed thereto that assists in 50 guiding the frame in the casing 7, and a coil spring 39 is seated against the plate 38 and the plug 11, for yieldingly holding the controlling frame in bolt-projecting position. The spring 39 is stronger than the spring 55 37. The frame 32 has a longitudinal slot 40 therein and gear teeth 41 to constitute a rack-bar at one side of the slot. Two identical face plates 42 and 43 are provided to be suitably secured to the opposite sides 60 of a door, each being adapted to serve as an

escutcheon plate which has a key-hole 44 therein in alignment with the key-holes in the lock case to assist in rotatively guiding the key 23. For manually retracting the latch bolt a spindle 45 is arranged in the 70 holes 13 and 13' and extends through the slot 40, the spindle being fluted or provided with gear teeth 46 that are in engagement with the teeth 41, the spindle extending through the face plates in which it may be 75 suitably guided, the spindle being provided with knobs or handles 47 and 47' as is customary.

The apparatus may be quickly mounted on a door after simply boring a hole for the 80 lock case 7 and also small holes for the lock key and the spindle, the several parts being secured in place by means of screws. As is apparent, the lock case may be arranged in relatively inverted order for attaining reversibility as may be required on different doors, some swinging inwardly and others outwardly while some are hinged at one side and others on the opposite side of a door frame or casing, or the latching and locking apparatus may be inverted in the lock casing; also, the latch bolt may be inverted relatively to the lock bolt and the frame 32 as appears in Figure 9.

The invention is intended to be variously modified to suit conditions and especially to lessen the cost when required for very inexpensive buildings, the structure permitting the omission of either the latch bolt or the lock bolt and either one or both of the coil 95 springs.

In practical use, when the apparatus is constructed and mounted as described, the spring 39 holds that portion of the frame 32 that is rearward of the spindle 45 so as 105 to be stopped against the spindle, permitting the striker plate 4 to force the latch bolt back against the pressure of the weaker spring 37 while the door is being forcibly closed, the spring automatically projecting 110 the bolt into the keeper when the door is fully closed. The spindle 45 is to be turned so as to operate the frame 32 and retract the latch bolt to permit the door to be opened, the spring 39 forcing the spring 32 forward 115 when the spindle knob is released. The key 23 is inserted in one of the key-holes and into engagement with the teeth 21 and rotated in order to project or to retract the lock bolt.

What is claimed as new is:

1. A door latch and lock including a tubular case having a front plate on one end and a plug in the opposite end thereof, the front plate having an aperture therein, a beveled latch bolt and a lock bolt arranged together and guided in said aperture for relatively independent longitudinal movement, the latch bolt being provided on its inner end with a yoke having gear teeth, a 125

spindle rotatively guided in the tubular case and having gear teeth engaging the gear teeth on the yoke, a coil spring seated on said plug and the yoke, and a key to engage and move the lock bolt.

2. In a door latch, the combination with a tubular latch case with a front end, of a latch bolt comprising a bolt head and a shank fixed to the head, the head being movably guided in said front end, the shank having a cross-bar on its inner end, a yoke movably guided in the latch case and having a front plate on one end and a back plate on the opposite end thereof, said front plate having a slot therein loosely receiving said shank sidewise and permitting said cross-bar to engage the back of the plate, said yoke being provided with a toothed rack bar, a coil spring on said shank seated against said bolt head and the front plate of said yoke, a coil spring seated in the latch case and against the back plate of said yoke, and a spindle guided by the latch case and having gear teeth engaging said rack bar.

3. In a door latch and lock, the combination of a tubular case having a front plate fixed on one end and a plug removably secured in the opposite end thereof, the case having a key-hole and a bearing aperture to receive a spindle in the wall thereof, said front plate having a guide aperture therein and recesses extending from opposite sides of the aperture, a latch bolt movably arranged in the guide aperture and having grooves opposite to the grooves in the front plate, a yoke connected to the latch bolt, a spindle arranged in said bearing aperture and having connection with said yoke, and a lock bolt comprising a body movably guided in the tubular case and two lock bars guided in said recesses and in said grooves, said body having devices to be engaged by a key to be inserted in said key-hole to move the lock bolt.

In testimony whereof, I affix my signature on the 6th day of May 1924.

ALBERT JACKSON THOMAS.
